Thomas W. Ryer, citizen of Pennsylvania.

Letters Patent.

The Schedule referred to in these Letters Patent, and making part of the same, containing a description in the words of the said Thomas W. Ryer, himself of his Improvement in the Bark Mill.

Bark, after being prepared in the usual manner is thrown into a "Horizontal Separating Machine", which is a cylindrical Revolutionary wire" (Sieves) finer or coarser as may be found most advantageous, with interstices to produce longer short filaments of bark, according to the different interstices to may be in the wire work; the separated bark falls into a chest below the Separating Machine, throwing out at the end. The unseparated lumps or pieces of bark which may not be sufficiently ground, which falling into a Reservoir are from thence taken and placed in a common Bark Mill and after being ground is thrown into the Separating Machine, & goes through the foregoing process.
